UNITED STATES PATENT OFFICE.

JAMES BENJ. PARKER, OF KELLOGG, IDAHO.

MINERAL SEPARATOR.

Application filed April 10, 1922, Serial No. 551,321. Renewed March 12, 1924.

To all whom it may concern:

Be it known that I, JAMES BENJAMIN PARKER, a citizen of the United States, residing at Kellogg, in Shoshone County and State of Idaho, have invented certain new and useful Improvements in Mineral Separators, of which the following is a specification.

My present invention relates to improvements in mineral separators or washers of the rotary type wherein the flotation process of separating minerals from a mass of pulp is utilized. The primary object of the invention is to simplify this type of machine by reducing to a practical minimum the number of operating parts, compactly arranging the parts of the machine for facile and effective operation, and otherwise improving structures of this character as for instance in the means for aerating the mass of pulp in the separating tank or vessel.

The invention consists in certain novel combinations and arrangements of parts as will be more specifically pointed out and claimed hereinafter.

In the accompanying drawings I have illustrated one complete example of the physical embodiment of my invention wherein the parts are combined and arranged according to the best mode I have thus far devised for the practical application of the principles of my invention.

Figure 1 is a transverse, vertical sectional view through the separator involving my invention.

Figure 2 is a perspective view, enlarged, showing the rotary drum or agitator utilized for aerating the pulp.

Figure 3 is a detail perspective view of the rotary foam-conveyer for transferring the mineral bearing froth or foam to the launder.

The flotation tank 1 as shown is constructed of planks or boards with an open top for supplying the gangue or mineral bearing material which is deposited therein in suitable manner. Water is also supplied to the tank in the usual manner and the liquid mass in the tank is preferably maintained at the level indicated by the line W. L. in Figure 1. Within the tank is journaled to revolve a specially constructed drum or hollow agitator, cylindrical in form and comprising a pair of heads 2 through which the drum shaft 3 is passed. The drum shaft is

journaled in bearings 4, and the shaft is revolved anti-clockwise from a suitable source of power. The tank is preferably longer than it is wide and the drum and shaft extend longitudinally of the tank, the diameter of the drum being of such size as to cause the drum to occupy a considerable space within the tank. The perimeter of the drum at its upper portion projects above the water level, while at its lower portion the perimeter of the drum is near the bottom of the tank.

The rotary drum, or hollow agitator includes a series of spaced slats 5 secured at their ends to the edges of the spaced heads 2, and between the adjoining slats are slots 6 extending to the open or hollow interior of the drum. At the edges of the slats are attached beads or strips 7 extending along the outer openings or mouths of the slots 6. Thus it will be apparent that as the exposed upper portion of the drum revolves air may be admitted to the interior of the drum through these slots and as the revolving drum operates the confined air may pass through the submerged slots and rise to the water level to form the required froth or foam. Air bubbles are also created at the top of the drum where it is exposed, as the splash caused by the slotted portions of the drum as they are exposed and then submerged agitates the liquid material and assists in forming bubbles on the surface of the material in the tank. The beads on the drum it will be apparent provide a roughened exterior for the drum which results in agitating the liquid mass to assist in separating the minerals and also to provide air bubbles that float to the water level.

In connection with the rotary drum I also employ baffle plates as 8, 9, 10, 11 disposed above the drum and extending longitudinally thereof. These plates are supported in brackets 12 on the end walls of tank, and they may be adjusted toward or away from the periphery of the drum to decrease or increase the space therebetween. The function of these baffle plates is to cause the foam or froth to pile up on the surface of the mass in the tank in order that the foam, in large masses, may float and be drawn over the surface of the water line.

By constructing the side wall 13 of the tank on an incline the depth of the water or mass in the tank decreases toward the

launder or trough 14 at the side of the tank, and the mineral-carrying foam is gradually transferred toward the launder side of the tank and spilled over the upper edge 15 of the sloping side into the launder for further treatment.

To assist in the movement of the floating foam I utilize a rotary conveyer disposed at the discharge point of the tank just above the spill ledge 15. This conveyer includes a shaft 15 suitably journaled in the end walls of the tank and revolved from the drum shaft 3 as by a crossed belt indicated at 17, the direction of rotation of shaft 16 being the reverse of that of the shaft 3.

On the shaft 16 are a pair of spaced heads 18 and between these heads are suspended a pair of paddles 19 having pivotal end connections 20 with the heads so that the paddles or blades may hang in vertical suspension as the conveyer revolves with its shaft 16. Thus, in Fig. 1, it will be seen that the lower edges or free edges of the blades dip into the surface of the liquid in the tank and the alternating movement of the blades pushes the foam in successive masses over the spill way or discharge edge 15 of the

tank into the launder, thus carrying the mineral laden foam to the launder.

The continuous operation of the drum and of the rotary conveyer results in successive movements of the buoyant mass and the minerals are thus recovered by the flotation process for further treatment after being received in the launder.

Having thus fully described my invention what I claim as new and desire to secure by Letters Patent is:

In a separator the combination with a tank having a spillway, of a partially submerged cylindrical drum comprising spaced heads a shaft and means for revolving said shaft, spaced slats connecting said heads and forming slots in the drum, longitudinally extending beads on said slats, a series of longitudinally extending spaced baffle plates located above and in operative proximity to said drum whereby the froth is caused to pile up on the flotation surface, and means for conveying froth to said spillway.

In testimony whereof I affix my signature.

J. BENJ. PARKER
